UNITED STATES PATENT OFFICE.

PHILIPP SCHWARZ, OF BARMEN, GERMANY.

STAMPING PROCESS.

Application filed January 19, 1928, Serial No. 247,994, and in Germany July 26, 1924.

When in a single machine the two appertaining discs for making a two-part article, for example a button, are continuously stamped out of two continuously fed metal strips, hitherto the discs from the one strip have usually been laterally carried by a special transporting slide out of the range of one strip into the range of the other strip in order to enable the two discs to be united. 5 It has also been proposed to unite the two discs at a punch position lying between the two strips. According to the present invention a special transport device moving cross-wise with relation to the strip is dispensed 10 with, by arranging the strips to cross one over the other, so that the union of the two discs can be effected at the crossing point without lateral movements. With multi-part articles this arrangement can be repeated, the lowest strip being crossed two or 15 more times by other strips lying above it.

The strips are crossed at an oblique angle, so that the tools operating at the crossing point can be arranged next to one another, 20 in a straight line or row of such length as to operate upon as many discs as possible. The crossing angle is therefore preferably chosen so that rows of discs of the greatest possible length in each strip come into register, in the direction of which rows the tools 25 are arranged.

The invention is illustrated in the accompanying drawing in which the figure is a plan view showing two strips at the point 30 of crossing and the arrangement of the tools for acting thereon, unessential parts being omitted to avoid confusion in the illustration.

In the drawing, *a* is the lower metal strip 40 and *b* the upper metal strip crossing it. It has been assumed that tools at *n* in known manner stamp discs in the strip *a* in inclined rows, these discs not being separated from the strip but only domed or otherwise formed. The strip *b* in which discs are also first stamped crosses the strip *a* in such a manner that a straight inclined row of discs comes into register at the crossing point with an inclined row of discs in the lower

strip *a*. At *m* the tools are arranged in 50 line with these two rows of discs, which tools serve to punch the discs completely out of the upper strip *b* and to unite them with the corresponding discs in the lower strip *a*. This union can be of a preliminary 55 character, consisting merely in the smaller discs from the strip *b* being inserted in the domed or otherwise formed larger discs of the lower strip *a*. It has further been assumed that the discs preliminarily united in 60 this way, are conducted to tools at *o* which separate the discs from the strip *a* and effect the pressing together of the discs.

If a three part article is being made, when the discs must be stamped out of three strips, 65 the third strip is arranged between *m* and *o* so that it also crosses the lowest strip *a*. At this crossing point the third disc is united with the two others, the final union again being effected at *o*. In the same manner 70 four or any number of discs can be united.

The procedure after the preliminary union of the discs is subordinate to the invention; the lowest strip with the various other preliminarily united discs could be supplied to 75 another separate machine for finally uniting the discs.

It is also conceivable for the discs to be completely stamped out of the lowest strip *a*. In this case a transport band shown in dotted 80 lines could be provided in known manner below the lowest strip *a* which band receives the stamped out discs in corresponding counter punches and carries them parallel 85 with the strip *a* at proper intervals to the further operating points. In this case also a special laterally moving transport slide which carries the discs out of the range of one strip into the range of the other strip, 90 is unnecessary. This is of particular advantage when more than two discs have to be united, since then the transport band only moves under the lowest strip parallel therewith in order to carry the discs to the union points, that is to the crossing points of the 95 lowest strip with the various other strips.

Having now particularly described and ascertained the nature of my said invention
